CLAIM

The ornamental design for an anti-theft device, as shown and described.

DESCRIPTION

FIG. 1 is a top perspective view of an anti-theft device according to an embodiment of the present invention;

FIG. 2 is a bottom perspective top view of the anti-theft device of FIG. 1;

FIG. 3 is a front view of the anti-theft device of FIG. 1;

FIG. 4 is a rear view of the anti-theft device of FIG. 1;

FIG. 5 is a top view of the anti-theft device of FIG. 1;

FIG. 6 is a bottom view of the anti-theft device of FIG. 1; and,

FIG. 7 is a side view of the anti-theft device of FIG. 1.

Broken lines in the drawings depict unclaimed environmental subject matter.
